UNITED STATES PATENT OFFICE.

FRED H. DALE, OF MANHATTAN, KANSAS, ASSIGNOR OF ONE-HALF TO LE ROY EAKIN, OF MANHATTAN, KANSAS.

HOT-WATER HEATER FOR INCUBATORS.

1,160,497.

Specification of Letters Patent. Patented Nov. 16, 1915.

Application filed June 1, 1915. Serial No. 31,427.

To all whom it may concern:

Be it known that I, FRED H. DALE, a citizen of the United States, residing at Manhattan, in the county of Riley and State of 5 Kansas, have invented a new and useful Hot-Water Heater for Incubators, of which the following is a specification.

The object of my invention is to provide improved means for the maintenance of an 10 even temperature in the incubator; to provide a novel disk method of heat distribution; to provide a novel heat-escape pipe; and to provide an improved double damper system disposed above the incubator, 15 operatively connected with the heat-escape pipe and heat chamber and operated by the action of the thermostat within the incubator.

It is an especial object of my invention to prevent any waste of heat, and to provide 20 improved means for more quickly adjusting the supply of heat to the incubator than is shown in prior incubator heating systems.

It is also an object of my invention to provide the novel combination, disposition 25 and arrangement of parts illustrated and claimed.

I attain the objects of my invention by the mechanism illustrated in the accompanying drawings, in which—

30 Figure 1 is a side elevation of my invention, partly in section; Fig. 2 is a top plan; Fig. 3 is an end view; Fig. 4 is a section through the center of the hot water heater and heat escape pipe; and Fig. 5 is a section 35 on line 5—5 of Fig. 4.

Similar characters of reference indicate similar parts throughout the several views.

Referring to the accompanying drawings, I provide a suitable incubator body 1, having 40 a suitable bracket 2 for a lamp 3, having a suitable chimney 4 provided with a mica window 31. Chimney 4 is provided with a reduced upper end 5, from the top of which is fastened rod or wire 6 which 45 supports a plurality of disks 7 and a plurality of disks 8 in alternate relation, fastened together in spaced relation by rods 9. The larger disks 8 extend entirely across the chimney but are provided with a central 50 opening 10 through which the heated air may pass, while disks 7 are of less area, leaving an annular space between their outer edges and the wall of the chimney, through which the heated air may circulate, as indicated by the arrows in Fig. 4. A water

heater drum 11, surrounds the upper portion of chimney 4 and chimney end 5, as illustrated. It is provided with a cap 18 which may be removed to fill the heater drum with water, and is further provided with a suitable outlet or draw-off valve 19. Opening out of heater drum 11 is a central outward flow pipe 12, opening into end pipes 13, which in turn open into return flow pipes 14 and 15, as shown in Figs. 1 60 and 2, pipes 15 opening into cold water return member 16, terminating in a channel 17 through the lower part of water heater drum 1, as shown in Fig. 1, in section.

Within the incubator chamber I provide 70 a suitable thermostat 30, operatively connected with thermostat lever 29, which in turn is connected by rod 28 to damper raising lever 26, which is fulcrumed at 27 and connected at 25 to double damper lever 22. 75 Damper lever 22 is supported and pivotally mounted on bracket 21. Attached to one end of damper lever 22 is a damper 23 adapted to seat over the upper end 5 of the chimney member 4; while attached to the opposite 80 end of damper lever 22 is a damper 24, adapted to seat over the end of a heat escape pipe 20, opening out of the lower portion of chimney member 4 and adapted to permit of the escape of heat before its circulation about the disks in the chimney member 4, as shown in Fig. 4.

In operation, heating of the incubator chamber beyond the predetermined temperature at which the thermostat is set will cause 90 damper raising lever 26 to raise damper lever 22 at 25, thus opening damper 24 over heat escape pipe 20 and simultaneously closing end 5 of chimney 4. Heat escape pipe 20, when damper 24 is open, causes such a 95 suction or draft that it draws the heat at once away from the water heater drum and upper portion of lamp chimney 4, thus quickly lowering the heat of the water in drum 11 and lowering the temperature the 100 required degree in the incubator chamber. The heated air from the lamp in passing through chimney 4 is kept in constant circulation against the sides of the chimney by means of the alternate disposition of disks 7 105 and 8, the heated air circulating, as indicated by the arrows in Fig. 4, around the outer annular openings between the outer edges of disks 7 and the chimney and through the central opening 10 in disks 8. The heat- 110

ed air is thus kept in constant circulation against the walls of the chimney, thus heating the water quickly and preventing any waste of heat.

6 My heat escape pipe, it is important to note, is located outside the main heating chamber, thus more quickly permitting the reduction of temperature in the incubator than in heating systems heretofore devised 10 for incubators, and thereby insuring the maintenance of an even temperature in the incubator through the use of the double dampers in connection with the heat escape pipe. My heater structure and incubator interior is of all metal, thus avoiding absorption of moisture from the eggs.

What I claim is:

1. The combination of an incubator having a water heater drum exterior to the incubator chamber, a heating flue extending therethrough having its upper end of reduced size and the lower portion of relatively large size and having baffle plates in said lower portion to increase the heating power, a heat escape pipe opening out of the base of said flue below the heater drum and having its upper end substantially aligned with the top of the flue, dampers disposed over the top of the heating flue and the top 25 of the heat escape pipe, and pivoted means operatively connecting said dampers with a thermostat to simultaneously raise one damper and lower the other, whereby to quickly regulate the temperature of the incubator.
2. The combination of an incubator having a water heater drum exterior to the incubator chamber, a heating flue extending therethrough having its upper end of reduced size, a heat escape pipe opening out 30 of the base of said flue below the heater

drum and having its upper end substantially aligned with the top of the flue, dampers disposed over the top of the heating flue and the top of the heat escape pipe, means operatively connecting said dampers with a 45 thermostat to simultaneously raise one damper and lower the other, a central pipe opening out of the upper portion of the heater drum for the outflow of water, and return pipes extending around the incubator chamber, and a pipe opening into the base of the heater drum into which said outer return pipes open, whereby to effectively and evenly heat the incubator chamber.

3. In a hot water incubator system, a hot 50 water drum having means for the outflow of water to the incubator and its return to the base of the heater drum, a heating chimney extending through the drum, a heat escape pipe opening out of the base of said heating 55 chimney and positioned exterior to the incubator chamber, operatively connected dampers positioned to seat over the heat escape pipe and the heating chimney end, means thermostatically controlled from 60 within the incubator for alternately operating said dampers to conform with temperature changes, and alternately arranged spaced large and small disks suspended in 65 horizontal position within the portion of the heating chimney extending through the heater drum, the large disks having central 70 openings, whereby heated air is kept in constant circulation against the sides of the chimney in passing the smaller disks, to rapidly heat the water in the drum.

FRED H. DALE.
